(57) **CLAIM**

The ornamental design for a plate, as shown and described.

DESCRIPTION

FIG. 1 is a side view of a plate showing my design;
 FIG. 2 is a bottom plan view thereof;
 FIG. 3 is a top plan view thereof; and,
 FIG. 4 is a cross-sectional view thereof, on an enlarged scale, taken along line 4—4 of FIG. 3.
 FIGS. 3 and 4 show a series of concentric ribs and ridges that randomly vary in size and/or height as shown in the drawings.
